W. A. RINGLER

LOOSE LEAF BINDER

Original Filed Oct. 27, 1924

Patented Feb. 7, 1928.

1,658,419

UNITED STATES PATENT OFFICE.

WILLIAM A. RINGLER, OF PHILADELPHIA, PENNSYLVANIA.

LOOSE-LEAF BINDER.

Application filed October 27, 1924, Serial No. 746,017. Renewed December 24, 1926.

The object of my invention is to devise a novel binder wherein if desired the cover and the binder can be made from a single piece of material.

With the above and other objects in view which will hereinafter appear, my invention comprehends a novel construction of loose leaf binder.

It further comprehends a novel loose leaf binder in which the backing and binder can be made from a single sheet of material.

It further comprehends a novel loose leaf binder in which the binder is formed by a folded portion of material, the base of which is secured together in any desired manner, one of the folds having a hook, and means being also provided for scoring the filing sheets.

Other novel features of construction and advantage will hereinafter more clearly appear in the detailed description and the appended claims.

For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention is not limited to the precise arrangement and organization of these instrumentalities as herein set forth.

Figure 1 is a plan view of a loose leaf binder embodying my invention.

Figure 2 is a plan view on a different scale of a portion of the blank from which the binder is formed.

Figure 3 is a section on a different scale on line 3—3 of Figure 1.

Figure 4 is a section on a different scale on line 4—4 of Figure 1.

Figure 5 is a section on a different scale on line 5—5 of Figure 1.

Figure 6 is a sectional view showing more particularly the manner in which a sheet is scored.

Figure 7 is a sectional elevation of a scored sheet for insertion in the binder.

Similar numerals of reference indicate corresponding parts.

Referring to the drawings:

1 designates a blank of sheet material from which the backing or cover and the binder are formed, the blank being scored as at 2 to

facilitate the proper bending of the blank. The blank may be of any material, but for the sake of economy in manufacture it is preferably made of paper. 3 designates the cover, 4 the binder and 5 the sheets carried by the binder.

The central portion of the blank 1 is folded on the scored or weakened lines to form the binder, seen in Figure 2, and from which it will be seen that the fold 6 has an inturned hook portion or locking flap 7. 8 is an intermediate spacing fold connected with an outer fold 9 which may be of different height than that of the fold 6. These folds are secured together by fastening devices 10 which may be paper clips, as shown.

The fold 9 has secured to its outer face a flat strip of material 11 secured thereto at its outer portion by adhesive or other suitable fastening means.

This strip 11 enables one to score the sheets 5 as at 12, see Figure 7, to form a rearwardly extending flange or flap 13. The cover 3 has secured to it, for example, by adhesive, a covering strip 14. The inner portion of the hook 7 is cut away as at 15 to form a tongue 16 which facilitates sliding the sheets 5 into position.

The slot 17 formed between the hook 7 and the fold 9 is closed at one end by means of the U-shaped strip 18 which forms a sheet stop and which is secured to the folds 6 and 9 in any desired manner.

The sheets to be assembled in the binder are inserted, as shown in Figure 6 in dotted lines, beneath the scoring strip 11 and the juxtaposed side of the cover closed thereby forming on the sheet the rearwardly inclined locking or holding flap 13. The sheet is then brought into a position to have the flap 13 be received beneath the hook 7 and is slid forwardly until it strikes the stop 18.

My present form of loose leaf binder can be very economically manufactured as the binder and cover are formed from a single sheet of material which is preferably paper.

It is more particularly designed for a loose leaf binder for schools which can be so cheaply manufactured that it, with a dozen or more sheets of paper, can be sold for a few cents.

If additional sheets are desired they can be removed from an ordinary paper pad, scored, assembled and inserted together or one by one in the binder.

The folds are juxtaposed and secured to-

- gether in such a manner that the sheets are resiliently secured between the folds and can only be removed by sliding them longitudinally of the binder.
5. In a co-pending application, I have described and claimed a loose leaf binder which instead of being made of a single sheet of material is made up of a plurality of sheets of material.
10. Having thus described my invention what I claim as new and desire to secure by Letters Patent, is:
1. A loose leaf binder formed from a single sheet of material folded to provide 15 cover sections and record-sheet retaining means, the latter being formed by a double thickness of the sheet bent to a hook shape formation.
  2. A loose leaf binder comprising an integral sheet of material folded to form cover sections and outer and intermediate folds one of said outer folds terminating in a sheet-retaining flap, an independent strip disposed transversely of the binder and forming 25 sheet-scoring means carried by one of said flaps, and securing means for said folds.
  3. A loose leaf binder comprising a cover and a binding portion, said binder having a 30 plurality of folds one of which terminates in an inwardly extending flap of double thickness and extending transversely throughout substantially the width of the binder, forming record-sheet retaining means, and securing 35 means for said folds.
  4. A loose leaf binder comprising a cover and a binding portion, said binder having a plurality of folds one of which terminates in an inwardly extending flap, forming record-sheet retaining means, a strip disposed transversely of one of said folds and secured to such fold along the marginal edge of the strip to form a scoring device, and securing means for said folds. 40
  5. A loose leaf binder comprising a cover section and a binding portion, said binder being formed of an integral piece of material folded upon itself to provide outer folds and an intermediate spacing fold, one of said outer folds terminating in an inwardly extending sheet-retaining flap, a strip of material secured to one of said folds and extending therefrom to enable a sheet to be scored to be inserted between said strip and its fold, and securing means for said folds. 45
  6. A loose leaf binder having a plurality of folds forming a slot therebetween, one of said folds terminating in an inwardly extending sheet-retaining flap, means to secure the folds together, and a stop at one end of said slot. 50
  7. A loose leaf binder having a plurality of folds forming a slot therebetween to receive a sheet, one of said folds having an inwardly extending sheet-retaining flap, the flap-carrying fold at one end having a portion cut away to facilitate the assembling of a record sheet therewith. 55

WILLIAM A. RINGLER.
